The ornamental design for a mobile wheel repair facility, as shown and described.

DESCRIPTION

FIG. 1 is a cross-sectional top plan view taken along line 1-1 of FIG. 2 of an interior of a trailer for repairing car wheels, showing my new design;

FIG. 2 is a cross-sectional elevation view thereof taken along line 2-2 of FIG. 1;

FIG. 3 is a cross-sectional elevation view thereof taken along line 3-3 of FIG. 1;

FIG. 4 is a cross-sectional elevation view thereof taken along line 4-4 of FIG. 1;

FIG. 5 is a cross-sectional elevation view thereof taken along line 5-5 of FIG. 1;

FIG. 6 is a perspective view thereof looking in the direction of arrow 6 of FIG. 1 rearwardly and to the right side of the interior of the trailer; and,

FIG. 7 is a perspective view thereof looking in the direction of arrow 7 of FIG. 1 rearwardly and to the right side of the interior of the trailer.

The broken lines in the FIGS. 2, 3, 5 and 7 depict environmental matter and form no part of the claimed design and the dash-dot broken lines in FIGS. 6 and 7 form the boundary of the figure and form no part of the claimed design.
